UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR PREPARING WELTING.

1,201,450.

Specification of Letters Patent. Patented Oct. 17, 1916.

Application filed January 25, 1915. Serial No. 4,332.

To all whom it may concern:

Be it known that I, ANDREW EPPLER, a citizen of the United States, residing at Lynn, in the county of Essex and State of Massachusetts, have invented certain new and useful Improvements in Machines for Preparing Welting; and I do hereby declare the following to be a full, clear, and exact description of the invention, such as will enable others skilled in the art to which it appertains to make and use the same.

The present invention relates to machines for preparing welting for use in the manufacture of welt shoes, and while particularly applicable to the preparation of welting for Goodyear welt shoes, it may also be used in the preparation of other kinds of shoe weltings.

The object of the invention is to produce a machine by which grooved and beveled welting suitable for use in the manufacture of shoes may be prepared from a strip of leather without removing any of the grain side of the leather strip.

With this object in view, the invention consists of a grooving and beveling machine provided with means for supporting and guiding a leather strip and having grooving and beveling knives constructed, arranged and supported as hereinafter described and claimed.

The present invention will be clearly understood from the following description when read in connection with the accompanying drawing in which—

Figure 1 is a view in end elevation of a welt grooving and beveling machine embodying the invention in its preferred form; Fig. 2 is a detail sectional plan view illustrating the manner in which the leather strip is supported and guided, and also the manner in which the beveling knife is mounted and its relation to the strip guiding means and grooving knife; and Fig. 3 is a sectional view of the completed welting.

The machine illustrated in the drawing is adapted to operate upon a leather strip of indefinite length and of a width equal to the width of the grooved and beveled welting which is to be produced. The leather strip, indicated at 1, is supported, during its passage to the machine, by means of a bed plate or table 2 over which the strip, after being inserted in the machine, is drawn by the operator by hand. The table 2 is provided

with an upstanding ledge or shoulder indicated at 3 which forms a guide for one edge of the strip. The other edge of the strip is engaged and guided by a plate 4 secured to the table 2 by screws 5 passing through slots in the plate so as to permit a lateral adjustment of the plate toward and from the ledge 3 to accommodate leather strips of different widths. The plate 4 is provided with a lateral extension 6 which extends over the strip 1 so as to form, in connection with the table 2 and the two edge guides, a closed guide-way for the strip as it enters the machine. The leather strip, as it is drawn through the machine, is held down firmly against the table 2 by means of a presser foot 7 formed on the lower end of the slide 8 mounted in vertical guide-ways in the overhanging head of the machine frame 9. This slide is acted upon by a spring 10 connecting a pin 11 at the upper end of the slide 8 with a pin 12 on the frame of the machine. By means of this spring, the presser foot is held yieldingly against the leather strip and is allowed to rise and fall to accommodate any irregularities in the thickness of the strip.

The grooving and beveling knives of the machine are indicated respectively at 13 and 14. The grooving knife is held in a split clamp 15 carried by a block 16 mounted for vertical adjustment on the slide 8, the adjustment being effected by means of an adjusting screw 17 engaging a projection from the slide 8 and screwing into a projection from the block 16. The grooving knife is arranged to extend downwardly through an opening in the presser foot and to act upon the leather strip. By adjusting the block 16 vertically, the grooving knife can be caused to project below the presser foot so as to cut a groove of any desired depth in the welt and, by reason of the fact that the grooving knife is mounted upon the presser foot, the knife and foot are maintained in fixed relative position during the operation of the machine, and a groove of uniform depth is formed throughout the length of the strip regardless of inequalities in the thickness of the strip.

The beveling knife 14 is also mounted on the presser foot so as to rise and fall therewith and thus the bevel cut on the strip by the knife is of uniform width throughout the length of the strip and has a fixed definite

relation to the groove in the strip. The beveling knife extends across the inner edge of the strip and is arranged to cut a bevel extending from near the groove to the inner edge of the strip. The relation of the bevel to the groove is clearly shown in Fig. 3 in which the bevel is indicated at 18 and the groove at 19. In preparing welting it is usual to cut the groove in the flesh side of 10 the leather strip and it will be seen from an inspection of Fig. 3 that in the welting produced by the machine of the present invention, both the groove 19 and the bevel 18 are on the flesh side of the strip so that the grain 15 side 20 of the strip is left intact from edge to edge of the strip. The welting illustrated in Fig. 3 is intended for use in the manufacture of Goodyear welt shoes, the groove 19 being adapted to receive the stitches of the 20 inseam and the thin edge produced by the bevel 18 being adapted to be bent into the shoulder of the insole. With the welt grooved and beveled as in Fig. 3, the stitches of the inseam will pass through the strong 25 grain surface of the leather and there will be no break in this surface to detract from the appearance of the finished shoe as is sometimes the case when the ordinary form of welting is used in which a 30 portion of the grain side of the leather strip is cut away in forming the bevel. The cutting edge of the beveling knife acts on the edge of the welt strip close to the presser foot as clearly shown in Fig. 2 so that the 35 strip is acted upon by the knife when under complete control of the presser foot and table 2. The beveling knife is secured in a split clamp formed on the end of a short shaft 21 mounted in a split bearing in the 40 presser foot and clamped therein by a clamping screw 22. This construction permits an angular adjustment of the beveling knife and also a longitudinal adjustment of the knife in the direction of feed. Inasmuch as 45 the beveling knife is mounted on the presser foot, it is maintained in fixed position with

relation to the presser foot and grooving knife throughout the operation of the machine so that a uniform bevel is produced and the thickness of the portion of the strip 50 between the beveled surface 18 and the groove 19 is maintained constant.

To permit the presser foot, grooving knife, and beveling knife to be raised away from the table 2 when the leading end of the strip 55 1 is inserted in the machine, a cam 23, provided with a handle 24, is mounted on the pin 11 at the upper end of the slide 8 and is arranged to bear against the upper portion of the machine frame. 60

The nature and object of the present invention having been indicated, and a machine embodying the invention in its preferred form having been specifically described, what is claimed is: 65

1. A welt grooving and beveling machine having, in combination, a grooving knife, a beveling knife arranged to act on the same side and near the same edge of a welt strip as the grooving knife, and cut a bevel slanting from near the groove to the edge of the strip and means engaging both sides of the welt strip and extending into close proximity to the beveling knife for guiding the strip and holding it in position to be acted 70 upon by the knives. 75

2. A welt grooving and beveling machine having, in combination, a grooving knife, means for guiding a welt strip past the grooving knife in position to be acted upon 80 near one edge by the knife, a beveling knife arranged to act on the same side and near the same edge of the strip as the grooving knife, and cut a bevel slanting from near the groove to the edge of the strip, and a yieldingly mounted presser foot engaging the 85 strip and carrying both knives. 90
